UNITED STATES PATENT OFFICE.

GEORGE ZINK, OF CLEAR SPRING, MARYLAND.

OPERATING DEVICE FOR SWINGING GATES.

SPECIFICATION forming part of Letters Patent No. 325,144, dated August 25, 1885.

Application filed February 12, 1885. (No model.)

To all whom it may concern:

Be it known that I, GEORGE ZINK, a citizen of the United States, and a resident of Clear Spring, in the county of Washington and State 5 of Maryland, have invented certain new and useful Improvements in Operating Devices for Swinging Gates; and I do hereby declare that the following is a full, clear, and exact description of the invention, which will enable others skilled in the art to which it appertains to make 10 and use the same, reference being had to the accompanying drawings, which form a part of this specification, and in which—

Figure 1 is a perspective view of my improved gate-opening mechanism, showing the same applied to a gate in position for operation. Fig. 2 is a perspective view, in a different position, of the gate-post with the gate-hinges and tilting mechanism. Fig. 3 is a top 20 view of the same. Fig. 4 is a side view showing the gate tilted and ready to swing open, with broken lines showing the same in a closed position; and Fig. 5 is an elevation of the latch mechanism.

25 The same letters refer to the same parts in all the figures.

This invention relates to swinging gates; and it has for its object to provide a device or mechanism for opening and closing the same which 30 shall possess superior advantages in point of simplicity, durability, ease of adjustment and operation, and general efficiency.

With these ends in view, the invention consists in the improved construction and arrangement of parts, which will be hereinafter fully described, and particularly pointed out in the 35 claims.

In the drawings hereto annexed, A designates the main gate-post, and B is the gate, 40 which may be of any suitable construction. C is a plate, secured to the side of the post A near its lower end by means of a shank passing into or through the said post. Said plate is provided with a pair of upward-projecting 45 studs, D D, at right angles to each other, and with a perforation, E, forming a bearing for the lower end of the hinge-rod F. The upper end of the latter passes through the inner end of a bracket, G, secured to the side of the post 50 near its upper end, and extending outward to a position directly between the studs D D of

the lower plate, or at an angle of forty-five degrees to either.

The lower end of the hinge-rod is provided with a crank, H, having at its outer end a stud 55 or pintle, I, upon which the lower end of the gate is hinged by means of a perforated bracket, J. The upper end of the gate has a pin or stud, K, which is journaled in a slot, L, in the bracket G.

The upper end of the hinge-rod is provided with an angular lever, M, the arms of which, N and O, are bent, respectively, in an upward and downward direction, and provided with pivoted operating-rods P and Q, for the outer, 65 ends of which guide staples or bearings are provided at the upper ends of suitably-arranged posts R and S. When it is desired, the post R can be placed at an angle to the posts A and S, as shown in the drawings, so 70 that the gate can be operated by a person coming toward it from the side; or it can be placed on a line with the two posts, as shown in dotted line, and the rod P secured to the arm O instead of N; or said rod can be made long 75 enough to reach from one post to the other, and have a pin at its center to engage with the arm O. The arms of the lever being bent as shown, the operating-rods will in practice clear and not interfere with each other. 80

T designates the latch-post, which is provided with a beveled catch, U, adapted to engage a pin, V, secured to the end of the gate under one of the slats of the same. To the side of the said catch is pivoted a lever, W, which, 85 when the gate is to be opened by hand for the passage of a pedestrian, serves to lift the outer end of the gate, so as to disengage it from the catch and enable it to swing open a sufficient distance. The outer end of the gate is also 90 provided with a catch, X, adapted to engage a pin, Y, extending from the post S.

From the foregoing description, taken in connection with the drawings hereto annexed, the operation and advantages of this invention 95 will be readily understood. When the gate is closed, the crank at the lower end of the hinge-rod will be in a position at right angles to the gate. When it is desired to open the gate, and one of the operating-rods is pulled to that end, 100 the hinge-rod is given a one quarter-turn, thus throwing the crank at its lower end out in a line

with the gate, and tilting the lower inner corner of the latter in an outward and upward direction, thus lifting the outer end of the gate out of engagement with the latch. It will at the same time be noticed that the upper hinge-point of the gate is located at a point between the two stop-studs of the lower hinge-plate, thus tilting the upper inner corner of the gate in the direction in which the gate is to swing, thus causing it to turn or swing by its own weight until it reaches the post S, with the laterally-extending pin of which the gate-catch will engage, the slot L in the bracket G enabling the gate to tilt slightly, so as to enable the latch to catch. When the gate is to be closed, the operation is simply reversed.

Having thus described my invention, I claim and desire to secure by Letters Patent of the United States—

1. In a swinging gate, the combination of the gate-post, a plate near the lower end of the same, having a pair of stop-studs at right angles to each other, a bracket near the upper end of said post, extending directly between said stop-studs, a hinge rod journaled vertically in said plate and bracket, and having at its lower end a crank provided with a pintle, and at its upper end an angular lever, to which are connected pivoted operating-rods, and the gate hinged at its lower end to the hinge-rod crank, and at its upper end to the bracket near the

upper end of the gate-post, substantially as and for the purpose set forth.

2. The combination of the vertical hinge-rod having a crank at its lower end, and journaled at its lower end in a plate having stop-studs at right angles to each other, and at its upper end in a bracket extending directly between said studs, with the gate hinged at its lower end to the crank of the hinge-rod, and at its upper end in a slot of the said bracket, and provided with suitable latches or fastening devices at its outer end, substantially as and for the purpose herein set forth.

3. The combination, with a swinging gate constructed and arranged to operate as herein described, of a beveled catch secured to the post, and provided with a notch at the post, a horizontal lever pivoted to the side of said catch parallel thereto, and extending beyond both sides of the post, said catch and lever adapted to engage with a pin upon the gate, and said pin being placed below and parallel with one of the slats of the gate, substantially as and for the purpose set forth.

In testimony that I claim the foregoing as my own I have hereunto affixed my signature in presence of two witnesses.

GEORGE ZINK. [L. S.]
